T. L. GOBLE, OF ORANGE, NEW YORK.

Letters Patent No. 64,802, dated April 30, 1867.

IMPROVEMENT IN CARRIAGE-JACKS.

The Schedule referred to in these Letters Patent and making part of the same.

TO ALL WHOM IT MAY CONCERN:

Be it known that I, T. L. GOBLE, of Orange, in the county of Schuyler, and State of New York, have invented a new and useful Improvement in Carriage-Jacks; and I do hereby declare that the following is a full, clear, and exact description thereof, which will enable those skilled in the art to make and use the same, reference being had to the accompanying drawings, forming part of this specification.

This invention consists in an arrangement for raising the wheels of a carriage or other vehicle from the ground by operating a nearly horizontal rail by a lever, which is hung or pivoted eccentrically to a standard, as will be hereinafter described. The drawing represents a side elevation of my carriage-jack.

A represents the bed-piece, B the standard, to which the lever is attached. C is another standard, by which one end of the rail is supported; D is the lever; E is the rail; F is a short adjustable stand, which is pivoted to the standard C and to the end of the rail E; g represents notches in the rail E.

In operating with the jack it is run under the axle of the carriage, when the rail stands, as seen in the drawing, horizontal, or nearly so, and with the lever D elevated as seen in the drawing. The end of this lever, which is pivoted to the standard B, is in the form of a circle. The fulcrum of the lever is at f on one side of the centre of the circle, or placed eccentrically. The other end of the rail is pivoted to the short stand F at J. Now, with the jack rail E under the axle as before mentioned, if the lever is depressed and the carriage raised, the lever and the rail will assume the position indicated by the red lines in the drawing, and the small stand F will stand upright, as seen, and in this position the jack will stand firmly with its burden, as the pivot h will stand directly over the fulcrum, and there will be no tendency in the lever to fly up. The distance from the fulcrum of the lever f to the pivot h is so short that the leverage is very great, and heavy weights may be raised with the greatest ease. The arrangement is so plainly set forth in the drawing that further description is deemed unnecessary.

What I claim as new, and desire to secure by Letters Patent, is—

1. The notched rail E, pivoted at one end to the eccentric-lever D, and at the other end to the pivoted adjustable stand F, substantially as described for the purpose specified.
2. The adjustable stand F, pivoted to the notched rail E, which is operated by the eccentric-lever D, substantially as described for the purpose specified.

T. L. GOBLE.
